UNITED STATES PATENT OFFICE

141,929

DESIGN FOR A COMBINATION STAND AND SERVICE TABLE

William I. Evans, Los Angeles, Calif.

Application February 5, 1945, Serial No. 117,778

Term of patent 14 years

(CL D33—14)

To all whom it may concern:

Be it known that I, William I. Evans, a citizen of the United States, residing in the city of Los Angeles, in the county of Los Angeles and State of California, have invented a new, original, and ornamental Design for a Combination Stand and Service Table, of which the following is a specification, reference being had to the accompanying drawing, forming part thereof, in which:

Fig. 1 is a side perspective view of a combination stand and service table with the trays thereof adjusted in a single horizontal plane showing my new design;

Fig. 2 is a side perspective view of the combination stand and service table with the trays

thereof adjusted in three different planes vertically disposed;

Fig. 3 is a side perspective view of the combination stand and service table with the trays thereof adjusted in three different planes in a stepped relationship; and

Fig. 4 is a rear view of the upper portion of the combination stand and service table with the trays thereof adjusted in the three vertically disposed planes.

I claim:

The ornamental design for a combination stand and service table, as shown.

WILLIAM I. EVANS.
